UNITED STATES PATENT OFFICE.

HENRY G. JOHNSON, OF EAST HAMPTON, CONNECTICUT, ASSIGNOR TO SUMMIT THREAD COMPANY, OF EAST HAMPTON, CONNECTICUT, A CORPORATION OF MAINE.

SEWING-MACHINE SHUTTLE.

Application filed June 21, 1922. Serial No. 569,888.

To all whom it may concern:

Be it known that I, HENRY G. JOHNSON, a citizen of the United States, residing at East Hampton, in the county of Middlesex 5 and State of Connecticut, have invented new and useful Improvements in Sewing-Machine Shuttles, of which the following is a specification.

This invention relates to a rotary shuttle 10 comprising a body member, having the usual beak and a head member hinged to the body member, and adapted to be removably seated on the latter, said members being provided with openings which coincide and 15 form a bobbin chamber when the head member is seated, means being provided, including a hinge ear on the head member and a spring tongue fixed to the body member, for yieldingly confining the head member 20 seated.

In a shuttle of this type, the spring tongue extends across one end of the bobbin chamber, and the shuttle includes a post adapted to engage the core of a ready wound bobbin, 25 the post being provided with a disk bearing on an annular flange on the head member, and with means cooperating with said tongue in forming a bearing permitting the rotation of the post and a bobbin thereon, 30 and in pressing the disk against said flange to prevent an undesirably loose and free rotation of the post and bobbin.

The invention is embodied in certain 35 improvements hereinafter described and claimed in the post and in the means cooperating with the spring tongue, for the purposes stated, the object being to provide a simple and durable embodiment of said means, adapted to permit thread to be drawn 40 freely across the axis of the post when the thread in unwinding from the bobbin, contacts with the tongue, and has to be drawn across said axis to the tension devices of the shuttle.

45 Of the accompanying drawings forming a part of this specification:—

Figure 1 is a plan view of a shuttle of the type to which my invention relates.

Figure 2 is a section on line 2—2 of Figure 1.

Figure 3 is a plan view, and Figure 4 an edge or side view of the post and disk.

Figure 5 is a sectional view showing the post before attachment to the disk.

The figures are drawn on a considerably 55 enlarged scale.

In the drawings, 12 represents the body member of a shuttle employed in certain types of the Singer sewing machine, and provided with a beak 13, a hinge pintle 14, and a circular opening 15. 16 represents the head member having a hinge ear 17 engaged with the pintle 14, and a circular opening 18 arranged as shown by Figure 2, to coincide with the opening 15, the two openings forming 60 a bobbin chamber. 19 represents a spring tongue attached at one end, as by a rivet 20 to the member 12, extending across one end of the bobbin chamber and bearing yieldingly at 65 its free end on a flat face formed on the ear 17, to hold the head section yieldingly seated on the body section, the head section being displaceable as indicated by dotted lines in Figure 2. The head section is provided 70 with an annular inwardly projecting flange 21 constituting a friction member cooperating with a friction disk 22 on a bobbin-engaging post 23.

The construction thus far described is well 75 known, the post being provided with yielding pressure means cooperating with the tongue 19 in forming a bearing for one end of the post, and in pressing the disk 22 yieldingly against the flange 21, to prevent 80 a too loose and free rotation of the post and of a bobbin engaged therewith.

In carrying out my invention, I construct the said post and the bearing and pressure means with which it is provided, as follows: 90

The post 23 is closed at one end and has a rivet forming extension 25 at its closed end, and an annular shoulder 26 surrounding said extension. The extension 25 is inserted in a central orifice in the disk 22 and is then upset to form a burr or flange confining the disk on the shoulder. The post is provided with a core 27, which is closed at the closed end of the post, and open at the opposite end. When the post is completed, the open end of the bore is slightly contracted to form an annular stop at 28. Before the bore is contracted, I insert therein a spring 29 and a polished steel ball 30, the ball having a loose fit in the bore, so 100 that it is adapted to rotate therein. After the insertion of the spring and the ball, I 105 slightly upset inwardly the open end of the

post, thus contracting the open end of the bore at 28, sufficiently to prevent the removal of the ball from the post, without preventing free movement of the ball toward the 5 inner end of the bore. The arrangement is such that a portion of the ball normally projects from the post and is held by the 10 spring against the tongue 19 when the head member is seated in the body member, the spring being thus compressed and acting 15 to press the disk 22 against the flange 21.

The closed end of the post enables a solid rivet extension 25 to be formed on the post, and constitutes an abutment for the spring 20 29. The bore contracted at its open end enables a ball to be inseparably confined in the post in such manner that the ball is in 25 rolling contact with the tongue 19, and not only constitutes a yielding end thrust bearing for one end of the post, but also enables thread which may contact with the tongue in passing from the bobbin to the usual tension devices with which the shuttle is provided, to be readily drawn across the axis of the 30 post, the ball turning freely in the post when the thread is drawn between the projecting portion of the ball and the tongue 19.

The bobbin here shown is of the ready wound variety, and is composed of a winding 32 of thread on a cop tube 33, in which the post is insertible, the post being preferably of polygonal form, as shown by Figures 3 and 4, so that it has obtuse angles adapted to slightly indent the tube.

I do not limit myself to the general shuttle construction shown and described, and may employ the improvements characterizing the invention in connection with a shuttle having any suitable frictional element substituted for the flange 21, and cooperating 40 with the disk 22, and any suitable pressure-supporting element substituted for the tongue 19 and adapted to cooperate with the ball 30.

I claim:

1. A shuttle having a bobbin chamber, a

frictional element at one end of the chamber, a pressure-supporting element at the opposite end of the chamber, a bobbin engaging post having a bore closed at one end and 50 open at the opposite end, said open end being contracted, a disk fixed to the closed end of the post and bearing on said frictional element, a spring within the post seated on the closed end thereof, and a ball yieldingly held by said spring against the contracted end of the bore, a portion of the ball normally projecting from the post and being adapted to roll on said supporting element. 55

2. A sewing machine shuttle comprising 60 a body member, a head member hinged to and adapted to be seated on the body member, said members being provided with circular openings forming a bobbin chamber when the head member is seated, the head member having an annular flange extending around the bobbin chamber, a spring tongue 65 fixed at one end to the body member extending across said chamber and having its free end engaging the head member to hold 70 said head member yieldingly seated, a bobbin core-engaging post closed at one end and having a rivet-forming extension at its closed end and an annular shoulder surrounding said extension, a disk united to the 75 post by said extension and adapted to frictionally engage the flange of the head member, the post having a bore opening through the end of the post opposite the disk and contracted at its open end, a spring seated 80 on the closed end of the bore, and a ball yieldingly pressed by the spring against the contracted end of the bore, and confined in the bore by said contracted end, a portion of the ball normally projecting 85 from the post and being adapted to roll on said tongue when the head member is seated.

In testimony whereof I have affixed my signature.

HENRY G. JOHNSON.
